(57) **CLAIM**

The ornamental design for magnifier tool, as shown and described.

DESCRIPTION

FIG. 1 is a front perspective view of a first embodiment of the design;
FIG. 2 is a rear perspective view of the design of FIG. 1;
FIG. 3 is a left side view of the design of FIG. 1;
FIG. 4 is a front view of the design of FIG. 1;
FIG. 5 is a right side view of the design of FIG. 1;
FIG. 6 is a rear view of the design of FIG. 1;
FIG. 7 is a top view of the design of FIG. 1; and,
FIG. 8 is a bottom view of the design of FIG. 1.

1 Claim, 6 Drawing Sheets

FIG. 1

FIG. 2

FIG. 3

FIG. 4

FIG. 5

FIG. 6

FIG. 7
